ELECTRIC RAZOR

Walter J. Pasinski, Howell, Mich.

Application June 22, 1938, Serial No. 215,083

3 Claims.

(Cl. 30—43)

This invention relates to shaving devices of the type more commonly known as dry shavers or electric razors, and pertains more particularly to that portion of the razor known as the cutting head.

The general object of this invention is to provide an improved electric razor.

Another object of this invention is to provide a more effective cutting head which may be moved over the face of the user in any direction.

A further object of this invention is to provide a cutting head which has a greater shaving area than those used heretofore.

A still further object of this invention is to provide an electric razor which requires less energy to operate than the usual razor of this type.

An additional object is to provide a simple direct drive for an annular, oscillatory cutting head set at an angle to the handle.

Other objects and their resultant advantages will be apparent from the following description, taken in connection with the drawing, in which:

Figure 1 is a side elevation of an electric razor embodying the novel cutting head of this invention;

Fig. 2 is a front elevation with a portion of the casing cut away to illustrate diagrammatically the electric driving motor and driving connections;

Fig. 3 is a separated perspective of the several parts of the cutting head; and

Fig. 4 is a section through the cutting head taken along line 4—4 of Fig. 2.

As usual in this type of device, the operating mechanism is mounted within the handle and the cutting head is carried by one end of the handle. Accordingly, in the device of the present invention, a housing 2 comprises the handle of the electric razor and the upper end of the housing or handle is recessed to detachably receive the body or supporting portion 3 of the cutting head which may be detachably secured to the casing by a set screw 4, as illustrated, or formed integrally with the casing 2. A circular member or spider 6 is attached to the body 3 by means of screws 7 with the plane of its face at an angle to the body 3 and casing 2. The member 6 is provided with fingers 8 threaded at their outer ends for detachably securing a shear plate or comb thereto, and is further provided with a central bore 9 for reasons later to be described.

Detachably connected to the spider 6 is a circular or cup-shaped stationary shear plate 11 adapted to be passed over the face of the user and having an annular end or wall shaving sur-

face 12, a depressed center portion 13 and an internally threaded peripheral wall 14 engaging the fingers 8. Any other suitable means for detachably securing the shear plate and spider may, of course, be employed. The annular shaving surface or end wall 12 is extremely thin, as is usual in this type of device, to permit shaving substantially at the surface of the skin, and is provided with substantially radial slots 15 having parallel side walls and being open at both ends. The width of each slot approximates that of the hair of the human beard and may be varied accordingly. This annular formation of the shaving surface and arrangement of slots provides a large shaving area having comb teeth extending in all directions which may be moved over the face of the user effectively in any direction.

Positioned between the shear plate and the spider 6 is an oscillatory cutter 16 comprising a disk having substantially radial cutting teeth 17 extending upwardly and outwardly from the disk portion. These cutting teeth 17 bear against the inner surface of the slotted annular wall 12 of the shear plate and have parallel edges which cooperate with the parallel edges of the slots 15 to clip any hairs entering the slots as distinguished from a shearing or scissor action.

The number of slots 15 and teeth 17 may, of course, be varied but it has been found desirable to provide more slots than teeth and preferably in the ratio of about three to one, although this may be varied to meet certain conditions such as size and stiffness of the hair to be cut. By providing a cutter with less teeth than slots in the shear plate, the cutting action does not occur at one point in the operation of the cutter, as is common in the usual type of cutter, but is spread throughout the entire oscillatory movement of the cutter, thus distributing the load and making it possible to use a less powerful operating motor. Furthermore, certain slots are always open to receive hairs throughout the full movement of the cutter.

The cutter is rotatably mounted upon a stud 18 (Fig. 4) which has a large end entering aperture 9 in the spider and a small end entering an aperture 19 formed in the cutter. The cutter is yieldingly urged into contact with the under surface of the shear plate by a coil spring 21 seated in the bottom of the aperture 9 and exerting pressure against the inner end of stud 18, thus forcing the cutter upwardly against the inner surface of the shear plate and maintaining clipping contact between the two elements. The

shear plate, cutter, and spider are fitted with a very slight clearance of less than the diameter of a hair between the inner annular surface 23 of the shear plate and the cutter and also between the inner annular surface 24 of the spider and the cutter. This prevents any hairs from entering the inner portion of the shear plate and cutter even though no spring 21 is provided. There is, however, little tendency for the hairs to enter the interior, because the spider mounting or manner of attachment of the body and shear plate leaves almost the entire rear side of the cutter head open, for the discharge of hairs cut by the cutter, and they will readily fall rearwardly and entirely free and clear of the cutting head. In other words, the cutting head is self-cleaning.

The cutter is oscillated by means of an arm 25 pivoted intermediate its ends at 26 to the casing 2. One end 27 of arm 25 enters an aperture in the cutter adjacent its periphery and the other end is formed with a fork 28 which engages an eccentric 29 on the motor shaft 30 of the driving motor 31 housed within the casing or handle 2. The motor 31 may be of any suitable type. Accordingly, as the motor 31 rotates, it oscillates the arm 25 and cutter 16 through a comparatively long stroke at a high frequency. It will be noted that although the cutting head utilizes an oscillating annular cutter set at an angle to the handle, the drive is very simple, being through a single eccentric cam and lever.

From the foregoing description it will be apparent that the essential parts of the novel cutter head may be manufactured cheaply. For instance, the body member 3 may be molded upon the casing 2 or die cast as a separate part, whereas the remaining parts, such as the shear plate 11 and cutter 16, may be stamped and readily finished by grinding the contacting and cutting surfaces. These grinding operations are also simplified because the entire surfaces to be ground are exposed. In other words, manufacturing conditions are greatly simplified over those for the usual type of cutting head. Shaving is facilitated because of the large shaving surface area with the slots 15 extending in different directions, which makes it possible for the cutting head to be moved in any direction over the face of the user. In so doing, it will comb hairs growing in various directions into the slots 15, some of which are always open due to the difference in number of slots and cutter teeth.

It will be apparent to those skilled in the art that minor changes may be made in the details of construction without departing from the spirit and scope of the invention as defined in the appended claims.

I claim:

1. An electric razor comprising a handle, a cutting head mounted on one end of said handle, a circular grooved guard and shear plate on the

top of said head, a circular cutter mounted in said head to oscillate under and in cutting relation to said shear plate, said head being positioned on said handle so that the longitudinal axis of said handle intersects said cutter near its periphery, an electric motor in said handle having the axis of rotation of its armature shaft at right angles to the longitudinal axis of said handle, and a lever pivoted in said handle, one end 10 of said lever having a cam slot in which is positioned an eccentric cam fixed to said armature shaft and the other end of said lever extending substantially in line with the longitudinal axis of said handle to said head where it is positioned loosely in an opening in said cutter.

2. An electric razor comprising a handle, a cutting head fixed to one end of said handle with the plane of said head at an angle to the longitudinal axis of said handle, a circular, grooved 20 guard and shear plate on the top of said head, a circular cutter mounted in said head to oscillate under and in cutting relation to said shear plate and in a plane parallel to that of said head, said inclined head being positioned with respect to said handle so that the longitudinal axis of said handle intersects said cutter near its periphery, an electric motor in said handle having the axis of rotation of its armature shaft at right angles to the longitudinal axis of said handle, and a lever pivoted in said handle, one end of 25 said lever being operably connected with said armature shaft to be oscillated thereby and the other end of said lever extending substantially in line with the longitudinal axis of said handle to said head where it is directly connected to said cutter, whereby rotation of the motor armature rapidly oscillates the cutter in said inclined head.

3. An electric razor comprising a handle, a cutting head mounted on one end of said handle with the plane of said head at an angle to the longitudinal axis of said handle, a circular, grooved guard and shear plate on the top of said head, a circular cutter mounted in said head to oscillate under and in cutting relation to said shear plate and in a plane parallel to that of said head, said inclined head being positioned on said handle so that the longitudinal axis of said handle intersects said cutter near its periphery, an electric motor in said handle having the axis of rotation of its armature shaft at right angles to the longitudinal axis of said handle, and a lever pivoted in said handle, one end of said lever having a cam slot in which is positioned an eccentric cam fixed to said armature shaft and the other end of said lever extending substantially in line with the longitudinal axis of said handle to said head where it extends into an opening in said cutter slightly larger than the end of said lever, whereby rotation of the motor armature rapidly oscillates the cutter in the inclined head.

WALTER J. PASINSKI.
